UNITED STATES PATENT OFFICE.

ARTHUR E. RUDOLPHI, OF DOWAGIAC, MICHIGAN.

FURNACE.

1,379,723.

Specification of Letters Patent. Patented May 31, 1921.

Application filed February 23, 1921. Serial No. 447,153.

To all whom it may concern:

Be it known that I, ARTHUR E. RUDOLPHI, a citizen of the United States, residing at Dowagiac, county of Cass, State of Michigan, have invented certain new and useful Improvements in Furnaces, of which the following is a specification.

This invention relates to improvements in furnaces.

10 The main objects of this invention are:

First, to provide a furnace with an improved casing supporting structure which is adapted to be shipped or transported in the knock-down form and easily set up and

15 assembled by an unskilled workman.

Second, to provide a casing supporting structure having these advantages in which the parts are simple and economical to produce and when assembled are very securely

20 and rigidly supported.

Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated 30 in the accompanying drawings, forming a part of this application, in which:

Figure I is a side view of a furnace embodying the features of my invention partially broken away and partially in vertical 35 section on a line corresponding to line 1-1 of Figs. V, VI and VII.

Fig. II is a side elevation of the body of the furnace.

Fig. III is a front view of the inner casing frame.

Fig. IV is a detail side view showing the inner casing frame mounted upon the furnace body.

Fig. V is a front elevation with the inner 45 casing and front plate in position.

Fig. VI is a horizontal section on a line corresponding to line 6-6 of Fig. I.

Fig. VII is an enlarged detail horizontal 50 section on a line corresponding to line 7-7 of Fig. I.

Fig. VIII is a detail view of the inner casing frame on a line corresponding to line 8-8 of Fig. IV.

Fig. IX is a fragmentary front elevation 55 with the front plate removed.

Fig. X is an enlarged detail horizontal

section on a line corresponding to line 10-10 of Fig. IX.

Fig. XI is a detail horizontal section on a line corresponding to line 11-11 of Fig. IV.

In the drawings similar reference characters refer to similar parts throughout the several views, and the sectional views are taken looking in the direction of the little arrows at the ends of the section lines.

Referring to the drawings, the furnace body is designated generally by the numeral 1 and has forwardly projecting ashpit and combustion chamber passage members 2 and 3 respectively. As the details of the furnace form no part of my present invention, I do not further describe the same herein. The inner casing in the embodiment illustrated has walls 9, 9' spaced to provide an insulating air chamber.

I provide an inner casing frame for supporting the inner casing comprising uprights 4 carrying at their upper ends the cross top piece 5. These uprights 4 are secured to the ashpit passage member so that the frame is supported directly upon the body of the furnace. The upright members 4 are provided with inwardly projecting feet 4' which rest on the top of the ashpit and engage the lugs 6 thereon, the tapered keys 6' being inserted through the lugs to secure the uprights in position. The frame is further secured by the yoke 24 which engages a lug 25 on the combustion chamber passage 26, the yoke being retained on the lug by the key 27.

At its ends the yoke is provided with downturned ears 28 which engage the rearwardly projecting lugs 29 on the rear sides of the uprights and are retained thereon by the keys 30. The cross bar 5 rests in slots 31 in the upper ends of the uprights. The parts of the inner casing frame may be formed as castings and are easily assembled upon the furnace body.

The upright members 4 are provided with outwardly projecting flanges 7, while the top cross member 5 has forwardly projecting upwardly facing lugs 8. The inner casing has an opening at the front and is arranged with its ends lapped upon the flanges 7 and secured thereto by the bolts 10. The top edge 11 of the casing member opening is engaged with the lugs 8 of the cross member 5, the cross member being curved to fit within the casing as is shown in Fig. VII. The inner casing is supported at the rear

by the arms 12 attached to the furnace body. This provides a rigid support for the inner casing. In erecting, the body is first placed, the inner casing frame mounted theron 5 and the inner casing mounted on the frame. The inner casing frame and the arms constitute a complete support for the inner casing.

I provide a front plate 13 carrying the 10 ashpit, fire and cleanout doors, and having side flanges 14 and a top flange 15. This front plate is secured to the passage members 2 and 3, the same being provided with bolt engaging lugs 16. The front plate is 15 arranged against the edge of the inner casing frame as shown, the front plate being preferably provided with a rib joint member 17, while the casing frame has a coacting groove joint member 18,—see Figs. I 20 and X.

The outer casing 19 is mounted upon the base ring 20 and has an opening to receive the face plate, the edges of the opening being secured to the flanges 14 of the face 25 plate by the bolts 21.

The structure illustrated is of the type generally designated as pipeless or one register furnaces, the register 22 having a central hot air section and a surrounding or 30 border cold air section 23, so that in use the air circulates downwardly through the section 23 between the casings and upwardly under the lower end of the inner casing which is supported in an elevated position, 35 as shown in the drawings, around the furnace body upwardly through the hot air register.

Structures embodying my improvements are very easily assembled by unskilled 40 workmen and when assembled are very strong and rigid. The parts may be readily shipped or transported in the knockdown.

I have not attempted to show certain modifications and adaptations which I 45 contemplate, as I believe the disclosure made will enable those skilled in the art to which my invention relates to embody or adapt the same as may be desired.

Having thus described my invention, what 50 I claim as new and desire to secure by Letters Patent, is:

1. The combination with a furnace body having projecting ashpit and combustion chamber passage members, a frame comprising 55 uprights having outwardly projecting flanges at their forward edges disposed at the sides of said passage members and secured thereto, and a cross top member disposed on said uprights above said passage 60 members and having forwardly projecting upwardly facing hook-like lugs, an inner casing member having an opening at the front disposed with the upper edge of the opening engaging said lugs and the side 65 edges lapped upon and secured to said

flanges of said frame, a front plate having forwardly projecting side and top flanges mounted on the ends of said passage members and overlapping said frame, said frame and front plate having coacting joint members, and an outer casing member secured to said front plate flanges. 70

2. The combination with a furnace body having projecting ashpit and combustion chamber passage members, a frame comprising 75 uprights having outwardly projecting flanges at their forward edges disposed at the sides of said passage members and secured thereto, and a cross top member disposed on said uprights above said passage 80 members and having forwardly projecting upwardly facing hook-like lugs, an inner casing member having an opening at the front disposed with the upper edge of the opening engaging said lugs and the side 85 edges lapped upon and secured to said flanges of said frame, a front plate having forwardly projecting side and top flanges mounted on the ends of said passage members and overlapping said frame, and an outer casing member secured to said front plate flanges.

3. The combination with a furnace body having projecting ashpit and combustion passage members, an inner casing frame 95 comprising uprights and a top cross member mounted on said passage members, an inner casing having an opening at the front disposed with the side and top edges of the opening engaging said frame, a front plate 100 mounted on said passage members and an outer casing member secured to said front plate.

4. The combination with a furnace body having projecting ashpit and combustion 105 chamber passage members, a frame comprising uprights having outwardly projecting flanges at their forward edges disposed at the sides of said passage members and secured thereto, and a cross top member disposed on said uprights above said passage 110 members and having forwardly projecting upwardly facing hook-like lugs, and an inner casing member having an opening at the front disposed with the upper edge of 115 the opening engaging said lugs and the side edges lapped upon and secured to said flanges of said frame.

5. The combination with a furnace body, a frame comprising uprights and a cross 120 top member mounted on said body, an inner casing member mounted on said body, a front plate having forwardly projecting side and top flanges mounted on said furnace body over said frame, and an outer casing 125 member secured to said front plate flange.

6. The combination with a furnace body, of a frame comprising uprights and a cross top member mounted on said body, an inner casing member having an opening at the 130

- front disposed with the upper edge of the opening supported by said frame cross member and the side edges by said uprights, an arm on the rear of said furnace body supporting the inner casing member at the rear, a front plate mounted on said furnace body over said frame, and an outer casing member secured to said front plate.
7. The combination with a furnace body, 10 of a frame comprising uprights and a cross top member mounted on said body, an inner casing member having an opening at the front disposed with the upper edge of the opening supported by said frame cross 15 member and the side edges by said uprights, a front plate mounted on said furnace body over said frame, and an outer casing member secured to said front plate.
8. The combination with a furnace body, 20 an inner casing frame mounted on said body, an inner casing member mounted on said frame, an arm on the rear of said furnace body supporting the inner casing member at the rear, a front plate mounted on 25 said furnace body in front of said frame, and an outer casing member secured to said front plate.
9. The combination with a furnace body, 30 an inner casing frame mounted on said body, an inner casing member mounted on said inner casing frame, a front plate mounted on said furnace body over said inner casing frame, and an outer casing secured to said front plate.
- 35 10. The combination with a furnace body having projecting ashpit and combustion chamber passage members, said passage members being provided with upwardly projecting lugs, of a casing frame comprising 40 uprights having inwardly projecting foot portions resting upon said ashpit passage member and engaging the said lugs thereon, said uprights having lugs on the rear sides thereof and vertical slots in their upper 45 ends, a yoke-shaped cross member engaged with said lugs on said uprights and with said lug on said combustion chamber passage member, and a top cross member engaged in said vertical slots in said uprights.
11. The combination with a furnace body 50 having projecting ashpit and combustion chamber passage members, said passage members being provided with upwardly pro-
- jecting lugs, of a casing frame comprising 55 uprights having inwardly projecting foot portions resting upon said ashpit passage member and engaging the said lugs thereon, said uprights having lugs on the rear sides thereof, a yoke-shaped cross member engaged with said lugs on said uprights and with said lug on said combustion chamber passage member, and a top cross member 60 on said uprights.
12. The combination with a furnace body 65 having projecting ashpit and combustion chamber passage members, said ashpit passage member being provided with upwardly projecting lugs, of a casing frame comprising uprights having inwardly projecting 70 foot portions resting on said ashpit passage member and engaging the lugs on said ashpit passage member.
13. The combination with a furnace body 75 having projecting ashpit and combustion chamber passage members, of a casing frame comprising uprights having inwardly projecting foot portions resting upon and secured to said ashpit, a cross member secured to said uprights and said combustion chamber passage member, and a top cross member 80 on said uprights.
14. The combination with a furnace body 85 having projecting ashpit and combustion chamber passage members, of a casing frame comprising uprights having inwardly projecting foot portions resting upon and secured to said ashpit.
15. The combination with a furnace body, 90 of a casing frame comprising uprights mounted on said body and having vertical slots in their upper ends, and a top cross member engaged in said slots in said uprights and provided with upwardly facing 95 casing supporting lugs.
16. The combination with a furnace body, 100 of a casing frame comprising uprights mounted on said body and having vertical slots in their upper ends, and a top cross member engaged in said slots in said uprights.
- In witness whereof, I have hereunto set my hand and seal in the presence of two witnesses.
